BYERS W. KADEL, OF BALTIMORE, MARYLAND

FLUE-BLOWING APPARATUS

Application filed December 8, 1923. Serial No. 679,498.

The invention relates to flue blowing apparatus, and more particularly stated, involves an improved blower and nozzle adapted for use with fire tube boilers.

One of the principal objects of the invention is to provide a flue blowing apparatus for locomotive boilers, said apparatus including among other things, a blower casing adapted to be fitted to the exterior of the boiler and having mounted therein a movable nozzle designed to be projected into and withdrawn from the fire box of the boiler, and means operable through a single actuating member for transmitting a plurality of movements to the nozzle, said movements including the projection and withdrawal of the nozzle with respect to the fire box and an independent sweeping of the tubes thereby.

Another object of the invention is to provide a blower and nozzle for cleaning boiler tubes including in combination a casing having a steam chamber and movable nozzle therein adapted to operate as a valve member, and means including an arm or lever for positively controlling the projection and withdrawal movements of the nozzle through a single actuating member, said arm or lever being located at a distance from the nozzle, such for example, as the cab of a locomotive, and said actuating member being designed to impart the sweeping movement to the nozzle and being operable by means located in close proximity to said arm or lever.

A further object of the invention resides in the production of a blower nozzle for flue cleaning apparatus involving a casing provided with an inlet opening and a discharge nozzle portion, the interior of said casing being shaped to provide a relatively large cavity leading from the inlet opening to a constricted passageway forming a throat portion, said throat portion serving to more or less abruptly intercept an expansible pressure medium, thereby causing the same to accumulate within the cavity adjacent the throat portion for subsequent distribution therethrough into the nozzle portion through which latter the pressure medium is progressively expanded in its projection from the nozzle to the area to be treated.

A still further object of the invention is to provide a blower nozzle adapted to cause a steady and uniform discharge of an expanding pressure medium such as steam against the tubes to be cleaned, said nozzle being provided with a pronounced throat portion located between the inlet and discharge openings of the nozzle and disposed at an angle to the longitudinal axis of the chamber of the nozzle, said throat portion involving a relatively narrow elongated passageway of comparatively small area, the longest dimension of said passageway being less than both the diameter of the substantially cylindrical inlet opening of the chamber and the longest dimension of the flaring nozzle portion at the point of egress of the steam whereby said steam in addition to reacting against the interior structure of the nozzle due to its velocity, is also caused to be ejected on the expansion principle in a solid-like spray so as to operate upon all the tubes within the prescribed area at substantially the same pressure.

Flue blower nozzles now in use are primarily designed to deflect the high velocity steam after passing into the chamber portion of the nozzle, said steam being diverted through an intermediate curved portion and discharged through a flaring nozzle portion, this type of nozzle operating upon the reaction principle and showing considerable variations in the effective working pressure of the steam over the area subjected to the blast. In practice this type of nozzle acts to but partially clean the tubes, the hollow-like portions of the steam blast or spray failing to exert sufficient pressure to properly clean some of the tubes.

My invention has been designed to overcome these difficulties now experienced, reference being had to the accompanying drawings chosen to illustrate an embodiment designed for locomotive use, and in which:

Figure 1 is a plan view of the assembled blower and nozzle apparatus as applied to a locomotive, fragmentary portions only of which latter are included within the illustration.

Figure 2 is a vertical sectional view through

the blower casing and the associated parts as applied to the water leg of a boiler.

Figure 3 is a horizontal sectional view on the line 3—3 of Figure 2 with the several parts beneath said section shown in plan.

Figure 4 is a vertical sectional view on the line 4—4 of Figure 2, viewed in the direction of the arrows, and with portions in the rear of said section being shown in elevation.

Figure 5 is an end view of the controlling mechanism as mounted upon a supporting bracket suitably connected to the boiler or other frame-work within the cab of the locomotive.

Figure 6 is a vertical longitudinal sectional view through said controlling mechanism, portions of the supporting bracket and adjustable connections of said mechanism being shown in elevation.

Figure 7 is a horizontal sectional view through the controlling mechanism shown in Figure 6.

Figure 8 is a detail transverse vertical sectional view on the line 8—8 of Figure 6, viewed in the direction of the arrows.

Figure 9 is an enlarged detail sectional view through the flexible connection uniting the principal actuating member with the interconnecting link.

Figure 10 is a view in elevation of the improved nozzle viewed from the discharge orifice side thereof.

Figure 11 is a longitudinal sectional view through the nozzle and particularly the discharge opening and interior cavity or chamber communicating therewith.

Figures 12, 13 and 14 are detail transverse sectional views on the respective lines 12—12, 13—13 and 14—14 of Figure 11.

Figure 15 is a view of the improved apparatus as applied to the upper portion of the water leg of the boiler at a point permitting a maximum sweep of a large area of tubes and also located within the outermost or over-all dimension of the boiler.

Referring to the drawings in which similar reference characters designate corresponding parts in the several views, I have indicated in Figure 1 but a most fragmentary portion A of the cab of a locomotive, and only a portion of the boiler B, the improved flue blowing apparatus being shown in plan view with the intermediate portion of the actuating rod broken away. The boiler is provided with the usual combustion chamber C, the fire box sheet being indicated by the numeral 1 and the outer fire box sheet by the numeral 2. In Figure 15 the usual tube sheet 3 is partially shown, as are also the stray tubes 4 and mud ring 5 uniting and spacing the fire box sheets 1 and 2.

The blower portion of the apparatus comprises a body portion or casing 6 provided with a chamber 7 having an inlet opening 8 suitably connected to a source of supply of

steam, air or other substance under pressure and with which the flues are to be freed from soot, cinders and other adhering particles incident to the combustion of the fuel. Referring to Figures 2, 3 and 4, the chambered portion of the casing has an axially arranged portion and an inclined communicating passageway leading from the inlet 8. It is desirable to make the blower body or casing of as small over-all length as possible to provide for sufficient road clearances. The axially arranged portion of the chamber 7 is designed to receive a valve member 9, said member including a pipe or tube provided with a plurality of openings forming the ports 10 which are designed to establish communication between the chamber 7 and the discharge nozzle 11 included within and forming a part of the improved blowing apparatus. In the present construction the nozzle 11 to be hereinafter described in detail, is shown attached to one end of the pipe or tube forming the valve member 9. The ports in the valve member are preferably elongated and arranged peripherally of the pipe to permit a maximum and uninterrupted flow of the pressure medium while the steam is turned on, the axial portion of the chamber in which the valve member moves being formed with opposite end portions, one of which forms a closure wall or bridge 12 for said ports when the nozzle is withdrawn from operative position. When in operative position within the combustion chamber of the boiler, the inner ends of the ports 10 of the valve member are substantially alined or flush with the opposite end of the axial portion of the chamber, as best shown in Figure 2.

The blower casing is provided with a stuffing box 13 through which the valve member 9 moves, said stuffing box being preferably set at an angle, as shown in Figure 4, for the purpose of providing maximum clearance for portions of the operating mechanism of the nozzle, and also for permitting the reduction of the over-all length of portions of said operating mechanism. The interior of the stuffing box gland is formed with an oil chamber 14, an oil duct 15 communicating with said chamber for permitting the introduction of lubricating material to the pipe or steam tube constituting the valve member. The flanged portion of the casing which cooperates with the stuffing box gland is preferably notched, as at 16, to permit the introduction of lubricating material when the gland is drawn up against the outer face of said casing flange.

The outer end of the valve member 9 is provided with a closure in the form of a cap 17 preferably screw-threaded upon the pipe and being adapted to receive a plurality of connecting means through and by means of which the said valve member is reciprocated to effect the projection and withdrawal there-

of with relation to the fire box, and in addition, oscillated to sweep the tubes of the boiler. The cap 17 is provided with a projecting arm portion 18 carrying at its outer end a rounded head forming the ball of the ball and socket joint 19 through which joint the oscillating means of the valve member and nozzle is connected to said valve, this said joint also permitting the reciprocatory motion thereof. The cap 17 is also adapted to receive a yoke member 20 formed of yoke sections 21, each of which is provided with an extending stud or trunnion 22 arranged to project substantially in a horizontal plane 24 passing through the axis of the valve member. The yoke sections are connected together by means of rivets 23 or other suitable fastening devices, said sections being fitted within the annular groove or race-way 25 provided in the cap 17, and united to permit relative movement between said cap and yoke. This movement consists in the oscillatory or sweeping action of the valve member pipe through the arm 18 while the yoke 20 remains relatively fixed as far as any rotary movement thereof is concerned.

The valve member 9 is reciprocated through the yoke connection 20, and more especially by means of links 25 arranged upon each side of the blower casing with their outer ends pivotally connected to the studs or trunnions 22 and their inner ends pivotally connected at 26 to movable arms 27 of a straddle member 28 operatively supported upon the blower casing. The links 25 are, at their outer ends, suitably retained about their pivotal connections with the trunnions 22 by means of nuts 29 which are positioned upon the threaded extensions of the trunnions and further securely locked thereon by means of pins 30. The inner ends of the links 25, at their pivotal connections 26 with the arms 27, are supported upon relatively flat headed bolts 31 and maintained by nuts 32 suitably locked by pins 33. The flattened heads of the bolts 31 permit the links to be located relatively close to the side walls of the blower casing and, in addition, it will be seen that should the nuts 32 be lost from off the threaded ends of the bolts, said bolts cannot be lost and that the apparatus will continue to function until the nuts are replaced and the pivotal connections 26 rendered once more secure.

The straddle member 28 is preferably cast and is designed to provide a simple and compact actuating member through which the valve and nozzle are effectively operated with a comparatively small amount of lost motion. The casting 28 is designed to straddle a hollow boss or projecting portion 34 of the blower casing, the upper portion of each arm 27 of the casting being formed with a relatively large hub section 35 disposed adjacent the opposite ends of the boss 34. The boss

is adapted to receive a round bushing 36, said bushing being provided with a square opening 37 through which opening, and correspondingly squared openings 38 in the hub sections 35, the squared portion 39 of an actuating member 40 passes. This bushing forms a bearing, the wear incident to the operation of the device occurring between said bushing and the opening within the boss 34. As a result of this construction there is comparatively no wear upon the actuating rod itself, other than that occasioned by its reciprocatory action through the bushing and hub sections 35 of the straddle casting.

The actuating member or rod 40 is designed to impart a plurality of motions to the valve member and nozzle, said member constituting the single means referred to herein as controlling the several movements of the blower from a remote point, preferably in the cab of the locomotive. From this actuating member both longitudinal and rotary motions are imparted to the nozzle, the longitudinal or reciprocatory action of the nozzle being transmitted through the squared end 39 of the rod when it is caused to rotate, and the rotary or oscillatory motion of the nozzle is occasioned when the actuating member 40 is moved longitudinally, the oscillatory motion of the nozzle being transmitted through a link connection 41, clearly shown in Figure 1.

The link 41 comprises a portion of the means for oscillating the nozzle to effect the sweeping of the tubes when the nozzle is projected within the fire box. One end of the link connection 41 comprises the socket portion of the ball and socket joint 19 provided at the outer end of the cap 17, and the other end of said link connection is also designed to provide a socket connection for the ball and socket joint 42 interposed between the actuating member 40 and said link connection 41. Arranged within the link connection 41 is a turn-buckle 43, said turn-buckle being capable of adjustment so as to accurately determine the zone or area to be covered by the sweeping action of the nozzle. This adjustment is particularly effective when the blast from the nozzle at the extreme ends of the oscillatory path of travel of the nozzle is improperly positioned and extends above the tube sheet or has a tendency to cut into the bed of the fire. In this case the turn-buckle is adjusted to move the complementary rods 41^a and 41^b of the link connection and change the oscillatory path of travel covered by the nozzle. Reversely, it will be understood that should a positioning of the oscillatory path of travel of the nozzle in the other direction be desired, the turn-buckle 43 will be adjusted in the opposite direction.

To effect a still further adjustment of the

nozzle in its sweep of the tubes and limit its path of travel, I have provided an adjustable stop means carried by the squared portion 39 of the actuating member 40, which means will be hereinafter described.

6 The ball and socket joint 42 by means of which one end of the link connection is attached to the actuating member 40, is shown in detail in Figure 9, as is also a novel connecting means between the relatively squared portion 39 of the actuating member 40 and that portion of said rod which extends rearwardly of the locomotive into the cab. The joint 42 includes complementary socket members 44, one of which is spring-pressed against the ball 45 and the other of which is screw-threaded into the end of the link connection and bears against the opposite side of said ball. This form of ball and socket joint provides a reliable and at the same time sufficiently flexible connection to permit the translation of the respective longitudinal and rotary motions from the single actuating member into the rotary and longitudinal motions required of the nozzle. The connection between the relatively squared portion 39 of the actuating rod and that portion thereof disposed within the control of the operative, comprises the pin or bolt 46 provided 20 at one end with the ball 45 and threaded at the other end to receive the clamping nut 47 suitably locked in place by means of the pin 48. Surrounding the pin 46 is a crowned bushing 49, said bushing being fitted within 25 an opening 50 provided in the end of the actuating rod section 39, the sides of said opening 50 being formed straight or parallel to permit a slight rocking action of the bushing 49 within the opening. The bushing projects slightly beyond the outer opposite faces 30 of the end of the rod section 39 and has fitted thereagainst forked extensions or jaws 51 of a clevis 52 suitably pinned, as at 53, to the rod section 54 of the general actuating member 40 heretofore referred to. By this construction the desired amount of flexibility or play is obtained and the motion from the rod section 54 effectively transmitted.

50 The means for controlling the longitudinal and rotary motions of the actuating member and more especially the rod section 54, is shown in detail in Figures 5 to 8, inclusive, and comprises a slidably and rotatably mounted sleeve 55 suitably secured to the rod section 54 by means of pins 56 and internally threaded for a portion of its length at 57. The internally threaded portion 57 receives the threaded rod 58 which rod, when rotated 55 by means of the hand wheel 59, causes the sleeve 55 to move longitudinally. The hand wheel 59 is keyed to the outer end of the threaded rod 58. The threaded rod is provided with a flange or collar 60 by means of 60 which and the nut 61 the said rod is held rela-

tively fixed against longitudinal movement adjacent the end wall 62 of a housing 63.

6 The housing 63 receives the movable sleeve 55 which is fitted within bearing portions provided in said housing so as to permit the longitudinal sliding and rotary movements of the sleeve. A bracket 64 supports the housing 63 and is preferably formed integral therewith, said bracket having a base portion 65 capable of being laterally adjusted with respect to the boiler or other frame to which said bracket is attached. In my present embodiment the bracket 64 is shown adjustably attached to the horizontally projecting flange 66 of a T-iron 67 by means of bolts 68. The T-iron 67 is provided with elongated openings 69 which are adapted to receive suitable securing bolts for rigidly attaching the same to the boiler or other frame-work in the cab of the locomotive, said elongated openings also serving to permit vertical adjustment of the controlling means, as will be understood.

75 The rotary or oscillatory motion of the rod section 54 of the actuating member is imparted thereto by means of a projecting arm or lever 70 having a hand grip portion 71 and an associated latch control 72 adapted to be actuated when the hand grip 71 is clasped by the hand of the operative. The arm or lever 70 is provided with a hub section 73 adapted to surround the movable sleeve 55 at an intermediate gap or open portion 74 provided in the housing 63. The hub section 73 is provided with oppositely disposed key-ways 75 adapted to receive keys 76 which latter are 80 designed to extend into relatively long key-ways 77 provided in the movable sleeve 55 and preferably extending throughout the entire length thereof. The keys 76 are retained between the opposite faces of the housing provided in the gap portion thereof, as best shown in Figure 6. In this present construction of controlling means it will be seen that any movement of the lever or arm 70 will cause the rotation of the sleeve 55 and in turn move the actuating member for reciprocating the nozzle. This oscillatory or partial rotary movement is positively imparted to the sleeve 55 through the key connection at any longitudinal position of said sleeve, thereby insuring the withdrawal of the nozzle from the fire box as well as its projection thereinto irrespective of what radial position the discharge orifice in the nozzle may occupy.

85 It is desirable to limit the oscillatory movement of the lever 70 between predetermined points, said points being arrived at according to the throw or reciprocatory path of travel of the nozzle and valve member. These points are indicated by the numerals 78 and 79 and comprise depressions within the housing 63 adapted to receive the lower end of the latch bar 80. The latch bar 80 is of comparatively simple construction and is adapted to operate within an opening 81 provided in the

lever arm 70. A collar or flange 82 is provided on the latch bar and a spring 83 is interposed between said collar and the wall forming the closure at one end of the opening 81. The upper end of the latch bar is suitably headed to receive the bifurcated end of an arm 84 projecting from and movable with the hand grip of the latch 72. The foregoing construction of latch mechanism is economical to manufacture, reliable in operation and durable. The movable sleeve member 55 of the controlling means is preferably lubricated through an oil or grease cup 85.

The location of the improved blower, and more especially the casing or body portion 6 thereof, is generally effected by inserting a stay tube or sleeve 86 between the fire box side sheet and the outside fire box sheet, as shown in Figures 2 and 3, for example. One end of the sleeve 86 is expanded or beaded over the fire box side sheet, as at 87, and the other end thereof is faced off to receive a similarly faced off annular portion 88 provided on the portion of the blower casing 25 adjacent the boiler. The faced off annular portion 88 is preferably recessed, and provides, together with the faced off end 86^a of the sleeve 86 a tight and non-leakable joint. The blower casing is maintained tight 30 against the end of the sleeve by means of the nuts 89 positioned upon the threaded extensions of the stud bolts 90, which bolts serve to effectively support the blower casing upon the boiler.

In Figure 15 of the drawings there is shown an application of the blower body portion or casing to the inwardly curved portion of a boiler such as employed on the larger types of locomotives and wherein it is essential to provide ample side clearance. To effect a convenient installation of the boiler apparatus one of the boiler stay tubes 4 is removed, and there is inserted a tube or sleeve 91 with its axis preferably disposed 45 at an angle to the radial center line which passed through the removed stay bolt, said sleeve being disposed with its inner end relatively close to one of the adjacent stay tubes and having its outer end arranged relatively close to the adjacent stay tube located 50 upon the opposite side of the sleeve. The insertion of the tube or sleeve 91 in this manner provides a relatively long recess into which the nozzle is normally withdrawn and 55 protected from the heat of the fire box. The outer end of the sleeve 91 is faced off to provide a tight joint with the blower casing flange contacting with said faced off portion. In addition, the facing off of the abutted 60 surfaces serves to properly align the nozzle within the sleeve or tube and prevent its contacting with the inner surface of the sleeve when reciprocated therein. The inclination of the sleeve or tube 91 is sufficient to permit 65 the application of the blower body or casing

to the outer fire box sheet with the outside dimension of the blower casing and its operating means falling within the over-all lateral dimension of the boiler. With the nozzle disposed at an inclination and movable into the fire box at an angle which substantially bisects the area of the tube sheet to which the blast is projected, it will be obvious that maximum efficiency is obtained from the blast in removing the soot and other particles from the tubes, and especially from the forward ends of the tubes surrounding the superheater coils of the locomotive. In addition, it will be observed that the location of the nozzle at an angle to the horizontal and in the upper portion of the water leg of the boiler causes less likelihood of the jets or blasts of steam cutting into the fire. In all other respects the blower casing and operating mechanism are maintained the same and a further detailed description of this application of my improved flue blowing apparatus to the larger types of locomotive boilers will not be given.

The blower nozzle 11 is preferably cast and involves a casing 92 formed with a relatively large chamber 93. The chamber 93 is provided with an inlet opening 94 of substantially cylindrical contour, said opening being screw-threaded for attaching the nozzle to the inner end of the sleeve constituting the valve member 9. The opposite end of the chamber 93 communicates with a discharge nozzle portion 95, said nozzle portion being arranged at one side of the chamber and having communication therewith through a constricted passageway 96 forming the throat portion of the nozzle.

The throat 96 of the nozzle is arranged intermediate the inlet opening 94 and discharge nozzle portion 95, said throat involving a relatively narrow and elongated passageway disposed at an angle to the longitudinal axis of the chamber and having its longest dimension less than both the diameter of the inlet opening and the longest dimension of the nozzle portion.

The walls of the chamber 93 are laterally flared and are preferably designed to terminate at a point beyond the nozzle portion, the shape of said walls acting to abruptly intercept the high velocity steam immediately adjacent the throat portion whereupon it is subsequently discharged through said throat and permitted to uniformly expand through the nozzle portion toward the tube sheet of the boiler. The advantage of providing the chamber so as to underlie the full area of the throat is that the formation of a relatively large cavity adjacent the same insures a constant head of steam or other pressure medium into which the flowing high velocity steam rushes with the result that the velocity of the steam is reduced and an effective working pressure built up adjacent the constricted

passageway forming the throat so as to more uniformly deliver the steam through the nozzle portion in substantially a solid-like spray for uniform expansion and blowing of the tubes. This construction of nozzle operates very largely on the reaction principle, the expansion developed incident to the constant flowing of the steam being greatly subordinated to the reaction of the steam as the result of the introduction of the throat portion and the formation of the walls of the chamber adjacent thereto with relation to the nozzle portion. In other words, because of the relatively short length of the flaring orifice or discharge nozzle portion 95 and the relation of the chamber 93 to said orifice, the reaction or reflection of the steam or other fluid on the wall of the chamber 93 directly back of the orifice 95 has a greater effect in determining the satisfactory discharge of the fluid than does the mere flowing of the steam through the orifice.

The discharge nozzle portion is of a narrow flaring contour, one wall 97 thereof being disposed at substantially right angles to the longitudinal axis of the chamber which it intersects and the opposite wall 98 being arranged at an angle thereto. This discharge nozzle portion or orifice is preferably formed to permit the insertion of a plug gage whereby the orifice may be chipped and finished according to the measurements of said gage. This feature is important in that the rough projections sometimes occurring in the casting tend to set up eddies and cross currents within the nozzle which interfere with the uniform distribution of the steam. The blower nozzle is preferably shaped at its outer end to provide a contracted nose portion, the sides being suitably tapered and otherwise reduced to prevent the clogging of cinders or other particles between the nozzle and sleeve 86, it being obvious that should such cinders collect in the tube the projecting movement of the nozzle into the fire box will facilitate the removal thereof.

The sweep of the nozzle, and more especially the discharge nozzle portion thereof, is determined by the position of a limiting stop member 99 shown in the form of a movable block slidably positioned upon the squared extension 39 of the actuating member. A fixed collar 100 is provided on said squared portion 39 and forms an abutment against which the sliding block 99 strikes when the actuating member is moved in the direction of the arrow shown in Figure 1. The block 99 contacts with the end wall of the adjacent hub section 35 provided on the blower casting as a result of this reciprocatory movement and the limit of travel of the link connection 41 is thereby established, the said travel determining the oscillatory path of travel or sweep of the discharge orifice 65 against the tube sheet. For different paths

of travel it will be seen that different length slide blocks can be substituted or the stop collar 100 otherwise adjusted. This adjustment permits of various distances of travel of the nozzle and is particularly effective in adapting the present construction of blowing apparatus to the several designs and sizes of locomotive fire boxes. The distance of the reciprocatory movement of the nozzle into the fire box is determined by stop lugs 101 projecting from opposite sides of the blower casing and adapted to intercept the inward movement of the arms 27 and the inner ends of the links 25 adjacent the pivotal connections 26. The outward limit of travel is determined by the outward movement of the nozzle and more especially the end wall 102 thereof of contacting with the end of the blower casing which extends into the sleeve 86, as best shown in Figure 2. The passage of the latch bolt 80 into the depression 78 when the controlling lever 70 is moved, also provides a means for limiting the withdrawal movement of the nozzle into the recess provided in the tube 86.

In operation, the operative within the cab of the locomotive, causes the projection of the nozzle into the fire box by grasping the handle 71 of the lever arm 70 and rotating the same in the direction of the arrow shown in Figure 5, said movement causing the rotation of the actuating member 40. The squared end portion of the actuating member 40 rocks the straddle casting 28 and through the link connections 25 effects the inward movement of the nozzle. The latch member of the controlling lever arm 70 moves into the depression or notch 79 and serves to hold the nozzle in projected position within the fire box.

With the nozzle in projected position, the operative now rotates the hand-wheel 59 whereupon the sleeve 55 is caused to move longitudinally and impart to the actuating member 40 longitudinal movement. This longitudinal movement is imparted to the link connection 41 through the flexible ball and socket connection 42, and said link connection in turn imparts said longitudinal motion to the radially projecting arm 18, through the ball and socket flexible connection 19. The radially projecting arm 18 being provided upon the cap section 17 connected to the end of the valve member 9, causes the longitudinal movement of the link connection to partially rotate or oscillate the valve member and in turn the nozzle 11 which stands projected into the fire box. The longitudinal movement of the actuating member 40 is controlled by the adjustable stop block 99 hereinbefore referred to, and also the inner face of the end wall 62 of the housing 63 against which the sleeve 55 abuts. The reciprocatory or axial movement of the valve member and nozzle when being pro-

jected into the fire box, causes the ports 10 of the valve member to move from their covered position by the bridge portion 12 of the casing and establish communication between 5 the chamber 7 and the nozzle for permitting the projection of steam against the tubes. The steam as it passes into the relatively large cavity 93 in the nozzle is decreased in velocity sufficiently to permit of its angular 10 deflection through the flaring discharge orifice 95 and provide for its projection at substantially a uniform pressure over the predetermined area of tubes. The rotation of the hand-wheel 59 in one direction will cause 15 the nozzle to sweep the tubes from the uppermost groups thereof to the lowermost groups above the fire box, and the rotation of the hand-wheel in the opposite direction will cause the reverse action in the sweeping of 20 the tubes. The relative size of the adjustable block 99 and position of collar 100 determine the full sweep of the nozzle across the tube sheet, and the turn-buckle connection in the link 41 permits of a modified path of 25 travel of the nozzle within the maximum sweep of the tubes.

Upon the completion of the sweeping of the tubes by the full rotation of the hand-wheel 59 in both directions the operative 30 grasps the handle 71 of the lever arm and returns the same to its initial position with the latch engaged in the notch or depression 78. The preferred construction of controlling mechanism positively insures the withdrawal 35 of the nozzle from the fire box when this operation occurs irrespective of whether or not the operative has failed to turn the hand-wheel its full number of revolutions. This positive control of the nozzle 40 in effecting its withdrawal from the fire box prevents the burning of the nozzle and other injury should it be permitted to remain subjected to the high temperatures of the burning fuel. In addition, the positive 45 control serves to insure the projection of the nozzle into the fire box so that the tubes will always be subjected to the blasts of steam. The valve casing may be provided with an outlet 103 adapted to provide for 50 connection of an automatic drain for the chamber 7, or provide for the attachment of a drain valve.

An apparatus constructed in accordance with this present invention can be readily attached to locomotives of various sizes and types and easily controlled from the engineer's cab. The arrangement of the several parts as shown and described provided for their economical replacement as well as their inexpensive initial application to the locomotive.

I claim:

1. In a tube cleaning apparatus, the combination with a casing having a chamber, of 55 a tube movable in said chamber and provided

with a nozzle at one end thereof, a plurality of inlet ports provided in said tube, means connected to said tube for oscillating the same, means connected to said tube for closing the ports from communication with said 70 chamber, and a single rod for operatively controlling both of the aforesaid means.

2. A blower nozzle for flue cleaning devices involving a chamber having a nozzle portion leading therefrom and being provided with an inlet opening, said chamber having laterally flaring side walls terminating beyond the planes of the nozzle portion, a wall provided in said nozzle portion the plane of which is adapted to intersect said chamber, and a second wall arranged at an angle thereto, said nozzle having a restricted throat portion arranged between said chamber and nozzle portion and disposed at an angle to the longitudinal axis of the chamber.

3. A blower nozzle for flue cleaning devices involving a chamber provided with an inlet opening and a nozzle portion leading from the opposite end of the chamber, said chamber having laterally flaring side walls terminating beyond the planes of the nozzle portion, a wall provided in said nozzle portion the plane of which is arranged so that if continued it would intersect the chamber, and a second wall similarly arranged at an angle to the first mentioned wall, said nozzle having a restricted passageway forming a throat portion located between the aforesaid walls, where they join the chamber and disposed at an angle to the longitudinal axis thereof.

4. A blower nozzle of the class described comprising a casing having a chamber with flaring walls, one end of which is provided with an inlet opening and the other end of which is shaped to form a narrow flaring nozzle portion, said nozzle having a throat portion provided in the casing between the chamber and nozzle portion, said throat portion being constricted and elongated to a longitudinal dimension which is less than both the diameter of the inlet opening and the longest dimension of the flaring nozzle portion.

5. A blower nozzle of the class described comprising a casing provided with a chamber having a substantially cylindrical inlet opening and a narrow flaring nozzle portion, said chamber having a diagonal wall provided with a constricted passageway forming a throat portion between the chamber and nozzle portion, said throat portion involving a relatively narrow and elongated passageway disposed at an angle to the longitudinal axis of the chamber and having its longest dimension less than the diameter of the inlet opening and less than the longest dimension of the flaring nozzle portion.

6. A blower nozzle for flue cleaning devices involving a chamber having a nozzle portion

and an inlet opening, said chamber being provided with walls one of which extends diagonally to the axis of the inlet opening and is formed with a constricted passageway adjacent the nozzle portion, said passageway having a throat disposed at an angle to the longitudinal axis of the chamber, and said nozzle portion being provided with oppositely disposed outwardly flaring walls extending from the constricted passageway for receiving and distributing an expansible pressure medium such as steam.

In testimony whereof I affix my signature.
